C. C. ABBOTT

ELECTRIC HEATING UNIT

Filed Oct. 17. 1922

Inventor:
Charles C. Abbott,
by Alexander S. Hunt.
His Attorney.

UNITED STATES PATENT OFFICE.

CHARLES C. ABBOTT, OF PITTSFIELD, MASSACHUSETTS, ASSIGNOR TO GENERAL ELECTRIC COMPANY, A CORPORATION OF NEW YORK.

ELECTRIC HEATING UNIT.

Application filed October 17, 1922. Serial No. 595,182.

To all whom it may concern:

Be it known that I, CHARLES C. ABBOTT, a citizen of the United States, residing at Pittsfield, in the county of Berkshire, State of Massachusetts, have invented certain new and useful Improvements in Electric Heating Units, of which the following is a specification.

My invention relates to electric heating units particularly to sheath wire heating units, and has for its object the provision of simple, reliable and efficient means for supporting the terminals thereof.

More specifically my invention relates to improvements in sheath wire heating units of the helical core type, disclosed in my copending application, Serial No. 505,588, filed October 5, 1921, of which this application is a continuation in part. In heating units of this type the resistance conductor is imbedded in a compacted mass of granular insulating material enclosed in a metallic containing sheath. To the ends of the resistance conductor are secured terminals which project from the sheath. In the construction of the heating unit, the resistance conductor with the terminals attached is first temporarily secured centrally in the sheath, for example, by securing the outer ends of the terminals. The sheath is then filled with granular insulating material and swaged to compact the insulating material. I have found that it is advisable that means be provided for positively centering the inner ends of the terminals in the sheath during the construction of the unit, otherwise the terminals and resistance conductor may be displaced and grounded on the sheath.

In carrying out my invention, I provide insulating members on the inner ends of the terminals for holding the inner ends of the terminals centrally of the sheath. In one form of my invention these insulating members are shaped as washers, while in a modified form of my invention the insulating members are square.

For a better understanding of my invention reference should be had to the accompanying drawing in which Fig. 1 is a view partially in section of an assembled heating unit embodying my invention before the swaging operation; Fig. 2 is a view partially in section showing a com-

pleted heating unit embodying my invention; Fig. 3 is a sectional view similar to Fig. 1 showing a modified form of my invention; while Fig. 4 is a sectional view taken along the line 4—4 of Fig. 3, looking in the direction of the arrows.

Referring to Figs. 1 and 2 of the drawing, in one form of my invention the heating unit 10 comprises a metallic cylindrical containing sheath 11 which is filled with a suitable granular insulating material 12, such as magnesium oxide, in which is imbedded a helical resistance conductor 13 having a terminal 14 secured to each end. The inner end of each terminal 14 is provided with a threaded portion 15 on which is secured the resistance conductor 13 and also an insulating spacing member 16 made of a suitable insulating material, such as mica. In the assembly of the heating unit, a spacing member 16, shown in the form of a washer, is screwed on the threaded portion 15 of each terminal, and the terminals then secured to the ends of the helical resistance conductor by screwing their threaded ends into the convolutions of the resistance conductor as described and claimed in my copending application, Serial No. 549,636, filed April 4, 1922. Preferably the terminals are screwed into the turns of the resistance conductor until the latter engages the spacing washers. The resistance conductor 13 with the terminals 14 attached is then inserted in the sheath 11, the resistance conductor stretched to separate its turns, and the terminals secured against the longitudinal pull of the resistance conductor by means of washers 17, only one of which is shown, placed on the terminals and seated in the ends of the sheath, which ends are counterbored to receive them, and a suitable clip 18 secured on each terminal so as to bear against the corresponding washer 17. One of the washers 17, for example the left-hand one, as shown, is in the form of a star washer.

The insulating spacing washers 16 on the inner ends of the terminal fit loosely in the sheath 11 and serve the purpose of holding the inner ends of the terminals substantially central in the sheath, the outer ends of the terminals being centered in the sheath by the washer 17.

In the next step in the construction of the

heating unit the granular insulating material 12 is filled in the sheath 11 through the openings in the star washer 17, the sheath being held in a vertical position with the star washer uppermost and vibrated so as to shake the insulating material down past the spacing washers 16, which fit the sheath loosely enough to permit the insulating material to pass, and between the turns of the 10 resistance conductor. This vibration also tends to compact the insulating material. After the sheath has been filled with the powdered insulating material it is closed by means of a solid washer 17', which is inserted in the sheath over the star washer and clip 18, and the ends of the sheath bent or pinched over at intervals 19 so as to secure the washers at each end in place. The heating unit has now been assembled as shown in 20 Fig. 1.

The granular insulating material 12 is next compacted to a hard dense mass by reducing the diameter of the sheath by swaging, after which the ends of the sheath are 25 cut off to effect the removal of the washers 17 and 17' and expose the ends of terminals 14, and connecting lugs 20 of a suitable material, such as brass, secured to the terminals. These connecting lugs may be secured as described and claimed in my aforesaid copending application, Serial No. 549,636 by providing nicks 21 in the outer ends of the terminals, inserting the nicked ends in suitable recesses in the lugs 20 and then compressing 30 the material of the lugs laterally into the nicks. Insulating washers 22 may be placed over the ends of the sheath against which the conducting lugs 20 are tightly forced by reason of the slight elongation resulting 35 from their lateral compression, whereby the ends of the sheath are sealed. The heating unit is thus made moisture proof.

It will be observed that the inner ends 40 of the terminals 14 are held substantially central in the sheath by the spacing washer 16 during both the filling and swaging operations. As a result the powdered insulating material 12 is distributed and compacted uniformly around the terminals whereby the 45 terminals are thoroughly insulated from the sheath. Likewise the resistance conductor 13 is held central in the sheath so that the insulating material is compacted uniformly around it.

In the modified form of my invention, 50 shown in Figs. 3 and 4, I have provided a spacing member in the form of a square insulating block 16 made of a suitable material, such as lava, for centering the inner end of 55 each terminal. This spacing block is preferably held in place on the inner end of the terminal by providing a flattened portion 23 in the terminal near the threaded portion 15. The spacing block is seated against the shoulders 23' formed by this flattened por-

tion and is prevented from slipping off the terminal by the resistance conductor 13. The spacing block 16 is of such size that its corners engage with the inner surface of the sheath 11, as shown in Fig. 4. Ample 70 space is thus provided around the flat sides of the blocks for the insulating material to be filled past the blocks into all parts of the sheath. The method of manufacture of this modified form of my invention will be 75 understood with reference to the description of Figs. 1 and 2. During the swaging operation the lava block may crumble and become a part of the granular insulating material. The terminals and resistance conductor are thus effectively centered in the sheath so that the insulating material is compacted uniformly around them.

It will be observed that by means of the square spacing members the inner ends of the terminals can be more accurately centered in the sheath than with the round spacing members shown in Figs. 1 and 2, since the round spacing members must be sufficiently loose to permit the granular insulating material to be filled past them into the sheath. I have found that lava is a material which is particularly adapted for the spacing members. Spacing members made of lava do not have the tendency to break up or flake off during the vibration of the unit when insulating material is being filled in, which tendency is characteristic of the mica spacing members.

While I have described my invention as embodied in concrete form and as operating in a specific manner in accordance with the provisions of the patent statutes, it should be understood that I do not limit my invention thereto, since various modifications 105 thereof will suggest themselves to those skilled in the art without departing from the spirit of my invention, the scope of which is set forth in the annexed claims.

What I claim as new and desire to secure 110 by Letters Patent of the United States, is:—

1. An electric heating unit comprising a sheath, compacted granular insulating material in said sheath, a resistance conductor embedded and supported in said insulating material, a terminal for said resistance conductor embedded and supported in said insulating material, and an insulating member for centering said terminal in said sheath while the insulating material is put 115 in and compacted to secure said terminal.

2. An electric heating unit comprising a sheath, compacted insulating material in said sheath, a resistance conductor embedded in said insulating material, terminals for said resistance conductor embedded in said insulating material projecting from the ends of said sheath, and insulating spacing members on the inner ends of said terminals for holding the resistance conductor and termi- 125 130

nals central of said sheath while the insulating material is put in and compacted to secure them.

3. An electric heating unit comprising a sheath, granular insulating material in said sheath compacted by swaging to a hard and dense mass, a resistance conductor embedded in said insulating material, terminals for said resistance conductor embedded in said insulating material, and insulating spacing members on the inner ends of said terminals for holding the resistance conductor and terminals central of said sheath while the insulating material is put in and compacted by swaging the sheath whereby the resistance conductor and terminals are secured.

4. An electric heating unit comprising a sheath, compacted granular insulating material in said sheath, a resistance conductor embedded in said insulating material, terminals for said resistance conductor embedded in said insulating material, and insulating spacing members on the inner ends of said terminals for holding the resistance conductor and terminals central of the sheath while the insulating material is put in and compacted, said spacing members being adapted to permit said insulating material being filled into said sheath.

5. An electric heating unit comprising a cylindrical sheath, compacted granular insulating material in said sheath, a resistance conductor embedded in said insulating material, terminals for said resistance conductor embedded in said insulating material, and non-circular insulating spacing members on the inner ends of said terminals for holding the resistance conductor and the inner ends of said terminals central while the insulating material is put in the sheath and compacted.

6. An electric heating unit comprising a cylindrical sheath, compacted granular insulating material in said sheath, a resistance conductor embedded and supported in said

insulating material, terminals for said resistance conductor embedded and supported in said insulating material, and insulating spacing members on the inner ends of said terminals for holding the resistance conductor and terminals central of the sheath while the insulating material is put in and compacted, said spacing members being provided with flat sides past which said insulating material may be filled into said sheath.

7. An electric heating unit comprising a sheath, compacted granular insulating material in said sheath, a resistance conductor embedded in said insulating material, terminals for said resistance conductor embedded in said insulating material, and square insulating spacing members secured to the inner ends of said terminals for holding the resistance conductor and terminals central of the sheath while the sheath is being filled with the insulating material and swaged to compact it.

8. An electric heating unit comprising a sheath, compacted granular insulating material in said sheath, a helical resistance conductor embedded in said insulating material, terminals for said resistance conductor embedded in said insulating material having threaded portions on which the ends of said resistance conductor are screwed so as to be secured thereto, flattened portions forming shoulders on said terminals adjacent said threaded portions, and insulating spacing members secured on said terminals between said shoulders and the ends of said resistance conductor for holding the resistance conductor and terminals central of the sheath while the insulating material is put in and compacted whereby the resistance conductor and terminals are secured.

In witness whereof, I have hereunto set my hand this 13th day of October, 1922.

CHARLES E. ABBOTT.
